UNITED STATES PATENT OFFICE.

STANLEY W. HAYES, OF RICHMOND, INDIANA.

DERAIL.

Application filed December 5, 1922. Serial No. 604,982.

To all whom it may concern:

Be it known that I, STANLEY W. HAYES, United States citizen, residing in Richmond, county of Wayne, State of Indiana, have 5 invented the following described Improvements in Derails.

This invention is a hand operated derail having target operating connections constituting a positive lock against operation of 10 the derailing member by the target line, but interfering not at all with derailing-member-initiated movement of the target line, unauthorized or accidental operation of the target as by the dropping of a stone or other 15 weight on the target line being thereby precluded.

This derail, in common with that of my application of even date herewith Serial No. 604,981, filed December 5, 1922, by virtue of 20 lost motion connections has the characteristic of delivering a hammer blow to said connections in movement of the derailing member to open or closed position, thus insuring a vigorous completion of the movement of 25 the parts when once started and by the slamming of the derail block on to the rail dislodging foreign material as mud or ice therefrom and positively and properly seating or withdrawing the derail block. The connections in the case of both these derails 30 include an actuator with reference to which the derailing member is movable, said actuator and member having opposed abutment surfaces two of which are in contact at the 35 beginning of the stroke in either direction, but separate during the stroke as the derailing member acquires momentum, and the other two of which are brought into contact in the striking of the hammer blow.

The type of derail in which this invention is exemplified and in which it is most satisfactorily embodied, is one having a derailing member swinging off and on the rail, and in the derail illustrated the derailing 45 member and the actuator are pivoted eccentrically with reference to each other. The arrangement and connections are such that in either extreme position of the derail they occupy a substantially dead center position 50 thus precluding target-line-initiated movement, the lost motion characteristic of the connections nevertheless permitting derailing-member-initiated movement.

Referring to the drawings, Figure 1 is a 55 transverse section of the open derail; Fig-

ure 2 is a rear elevation corresponding to Figure 1; Figure 3 is a transverse section showing the derailing member just past mid-position in its railward movement; Figure 4 is a section transverse to the rail of the 60 closed derail; Figure 5 is a plan view of the open derail, and Figure 6 a detail.

The base of the derail is provided with front and rear walls 1 and 2, and sidewalls 65 3 and 4 having lateral spike flanges 5 with strengthening ribs 6, a roof 7 and upstanding lugs 8 receiving the hinge pin 9, on which is mounted to swing to and from the rail, the derailing member having the derail block proper 10 with hand hold 10^a (Fig. 2) 70 and the hinge-pin lugs 11 through which the pin 9 passes. The derailing member has abutment surfaces suitably rounded and shown as studs 12, 13 which for strength may be connected by a portion 14 making a 75 double or dumb-bell cam. The derailing member also carries a lug 15, the functions of which will presently appear. This double cam and lug 15 project inward from opposed intermediate walls of the derailing member 80 spaced to receive without undue sidewise play the actuator about to be described and which is so termed because, though itself actuated by the hand operated derailing member, it is the primary or actuating member of the connections. In the structure 85 illustrated, the actuator takes the form of a crank 16, the upper part of which is located in the space between the said walls on the derailing member and extends therefrom into and through a space in the roof of the base, the crank being pivoted eccentrically with reference to the derailing member and being so constructed that it can move 90 through the proper angle without interfering with the hinge pin 9 which is within its path. For this purpose it may be provided with a segmental slot 17 of a size to receive the hinge pin 9 without unnecessary play, the actuator being thus suspended from the 95 said pin, but such suspension though desirable is not essential. The preferred form of actuator has a pair of trunnions 18 mounted in vertical slots at each side of the actuator and confined between the front and rear walls of the slots, the actuator thus being free to swing in its own plane but being prevented from bodily movement transverse or lengthwise of the rail. These slots 100 are formed as parts of the roof as by de- 105

110 Fig.

pending and upstanding flanges having front and rear walls 19, 20 and side walls 21, 22, the former taking the thrust toward or from the rail and the latter serving to assist in preventing movement of the actuating member lengthwise of the rail, transverse rocking of the lever being prevented by the central walls and the lug 15 on the derailing member, said lug being opposed to the back of the recessed head 23 of the actuator. This recessed head fits over the abutment surfaces 12, 13 and its opposite walls 24, 25, serve as abutment surfaces corresponding respectively to abutment surfaces 12, 13, to which they are opposed. Rod 26 and arm 27 make up the target line connecting the actuator 16 with the target stand 28, a suitable arrangement being illustrated at the right of Figure 4 partly on a smaller scale.

It will now be apparent on reference particularly to Figs. 1 and 4 that in each extreme position of the derail both on and off the rail, the derailing member is locked against target-line-initiated movement, thus, if in Fig. 1 an effort is made to move the target line 26 to the right, the force is transmitted through the actuator 16 by its bearing surface 25 to the ear 13 on the derailing member which cannot be swung around the axis of its hinge pin 9 because the point of contact between abutment surfaces 25 and 13 is in a substantially radial line with reference to said pin and is thus substantially in line with said axis, the connections thus constituting a dead center lock against such movement. Similarly in Fig. 4 the axis of the hinge pin 9 and the contacting abutment surfaces 24 and 12 occupy the like relation with like effect. But these connections interpose no obstacle to actuation of the target line through the derailing member, which may be swung on or off the rail by the hand hold 10, and which then causes abutment surfaces 12 and 24 or 13 and 25, as the case may be, to slide relatively, and then separate, and which on acquiring momentum delivers to the actuator through the latter's abutment surface 25 or 24 a hammer blow by its own abutment surface 13 or 12.

The abutment surfaces or studs 12, 13 carried by the derailing member are preferably located symmetrically, being in the illustrated derail symmetrical with reference to a plane through the axis of pin 9.

Claims—

1. A derail comprising a derailing member adapted to be moved from a position upon the rail to a position at one side and operating connections adapted to be actuated by the derailing member but locking the derailing member against movement by said connections when off or on the rail.
2. A derail comprising a base, a derailing member mounted thereon and adapted to be moved from a position upon the rail to a

position at one side, a target, and operating connections from said derailing member to said target constituting a lock against target-line-initiated movement.

3. A hand operated derail comprising a base having spike flanges, a derailing member mounted thereon and adapted to be moved from a position upon the rail to a position at one side, and target connections associated therewith for operation by the derailing member but constituting a lock against target line operation of the derail member when on or off the rail.

4. In a derail, a derailing member, a connecting line, an actuator for said line, and operative connections between said derailing member and actuator constituting in themselves a lock against actuator-initiated movement of the derailer member when off or on the rail.

5. In a derail, a base, a derailing member pivoted thereon and operative connections immovable except by said derailing member.

6. In a derail, a pivoted derailing member, an actuator crank, a pipe line connected to said crank, and operative connections between said derailing member and crank constituting a dead center lock against transmission of movement through the crank to the derailing member in either extreme position.

7. In a derail, a base, a derailing member pivoted thereon, and operative connections comprising an actuator pivoted eccentrically with reference to said derailing member and having an abutment surface, said derailing member having an abutment surface spaced from and opposed to that of the actuator and adapted to strike the same a hammer blow after the derailing member has acquired momentum.

8. A derail comprising a base, a derailing member pivoted thereon, an actuator pivoted on the base eccentrically with reference to the derailing member, and a pivoted connecting rod connected to the actuator, said derailing member and actuator having a lost motion connection comprising opposed abutment surfaces separated at each extreme position of the derail but coming into contact as the derailing member acquiring momentum strikes the actuator a hammer blow.

9. A derail comprising a base, a derailing member movable thereon, an actuator pivoted on the base eccentrically with reference to the derailing member, and a connecting rod connected to the actuator, said derailing member and actuator having a lost motion connection comprising two sets of opposed abutment surfaces, one of which is in contact at each extreme position of the derailing member and the other of which comes into contact after the separation of the first set as the derailing member acquiring mo-

mentum strikes the actuator a hammer blow.

10. A derail comprising a pivoted derailing member having a fixed axis, an actuator, a connection therewith, said actuator being pivoted eccentrically with reference to the derailing member, and relatively movable cooperating abutment surfaces on said derailing member and actuator.

11. In a derail, a base, a derailing member, a pivot pin therefor mounted on the base, and a pivoted actuator hung on said pin and having a slot receiving the same and lying in the arc of a circle whose center is in the axis of the actuator, said derailing member and said actuator having opposed separable abutment surfaces constituting a lock against actuator-initiated movement.

12. In a derail, a base, a derailing member pivotally mounted on said base to swing on and off the rail, and an actuator pivoted below the derailing member with its axis in the same vertical plane and having a lost motion connection therewith.

13. A derail comprising a base, a derailing member pivoted thereon and an actuator pivoted eccentrically with reference to the derailing member and connected thereto by one way lost motion connections, the derailing member being free to operate said actuator by its momentum, but being locked against operation by said actuator.

14. A derail comprising a base, a derailing member mounted thereon to swing on a fixed axis therein on and off the rail, and an actuator pivoted eccentrically with reference to the derailing member, said derailing member and actuator having cooperating abutment surfaces free to separate as the derailing member is swung from either extreme position and other abutment surfaces coming into contact as the swinging derailing member strikes the actuator a hammer blow.

15. In a derail, a base, a derailing member, a hinge pin therefor, and a pivoted actuator having a slot receiving said pin and lying in the arc of a circle concentric with the axis of the actuator, said derailing member and said actuator having unconnected abutment surfaces contacting in open or closed position of the derail in substantially the line of dead centres to act as a lock against actuator initiated movement.

16. A derail comprising a base, a derailing member mounted thereon to swing on and off the rail, and an actuator pivoted eccentrically with reference to the derailing member, said derailing member and said actuator having opposed abutment surfaces forming operative connections from the derailing member to the actuator but acting as a lock against actuator-initiated movement.

17. A derail comprising a base, a derail-

ing member pivotally mounted thereon, an actuator suspended from the pivot pin of the derailing member, said actuator having trunnions, and means on the base for limiting motion of said trunnions transverse of the rail.

18. A derail comprising a base, a derailing member mounted to swing thereon off and on the rail and having a pair of abutment surfaces symmetrically located with reference to a plane through the axis about which the derailing member swings, and an actuator pivoted eccentrically with reference to said axis and having a pair of extended abutment surfaces cooperating respectively and alternately with opposed members of the pair of abutment surfaces on the derailing member.

19. A derail comprising a base, a derailing member mounted to swing thereon off and on the rail, and an actuator mounted on the base eccentrically with reference to the derailing member, said actuator and said derailing member having abutment surfaces spaced and arranged in pairs, one member of each pair in open and in closed derail position being in contact with each other and constituting a lock against actuator-initiated movement of the derailing member while permitting derailing-member-initiated movement.

20. In a derail an actuator having trunnions, a segmental slot above the trunnions and a recessed head above the segmental slot and provided with opposed walls.

21. A derail comprising a base, a derailing member mounted thereon to swing on and off the rail, an actuator mounted to swing on the base and having its axis below that of the derailing member, and a connecting rod connected to the actuator.

22. In a derail an actuator having a segmental slot and a recessed head above the slot and provided with opposed side walls.

23. In a derail, a base, a derailing member pivoted thereon, and a pivotally mounted actuator, the axis of the derailing member being above that of the actuator, and operative lost motion connections between said actuator and said derailing member.

24. A derail comprising a closed base, a derailing member pivoted thereon and having spaced intermediate walls, an actuator pivoted on the base and extending into the space between said walls and through a hole in the roof, and connections between said derailing member and actuator.

25. In a derail, a pivoted derailing member, an actuator, and a pipe line connected to the actuator, said derailing member and actuator having two sets of opposed abutment surfaces, one or the other of said sets being in contact in open position and in closed position of the derail and then lying substantially in the line of application of

- force by the actuator and substantially in line with the pivotal axis of the derailing member thus acting as a dead center lock against actuator-initiated movement, and
- 5 the members of the other of said sets being then in the line of application of force by the derailing member to the actuator and
- out of line with said axis, whereby the derailing member when moved toward or from the rail may initiate movement of the pipe ¹⁰ line.

In testimony whereof I have signed this specification.

STANLEY W. HAYES.
